UNITED STATES PATENT OFFICE

163,558

CHICKEN-PICKING FINGER

Seth S. Barker, Ottumwa, Iowa

Application January 28, 1950, Serial No. 7,548

Term of patent 14 years

(Cl. D11—1)

To all whom it may concern:

Be it known that I, Seth S. Barker, a citizen of the United States, and a resident of the city of Ottumwa, in the county of Wapello and State of Iowa, have invented a new, original, and ornamental Design for a Chicken-Picking Finger, of which the following is a specification, reference being had to the accompanying drawing, forming part thereof.

I claim:

The ornamental design for a chicken-picking finger, substantially as shown.

SETH S. BARKER.
